BLIND STITCHING DEVICE

John Jordan, Portland, Oreg.

Application November 25, 1938, Serial No. 242,147

6 Claims. (Cl. 112—140)

This invention is of a blind stitching device, in some respects similar to that disclosed and patented to me in my Patent Number 2,091,479.

It is an object of the present invention to devise a device for blind stitching that increases the utility of that disclosed in the patent mentioned, to make the parallel grooving of the jaw members, which when joined form needle-ways, unnecessary and to otherwise increase the general utility of the device, which will be apparent from the disclosure to follow and which is particularly to be ascertained by the claims.

This disclosure is hereinafter described in detail for the purpose of clearly explaining the preferred embodiment selected for the purpose. It is to be understood that the illustration herein is by way of example only, and not of limitation, that it may be applied to all other embodiments within the scope of the claims as hereinafter written.

I accomplish the objects named and others that will be at once apparent to those skilled in tailoring and related arts by the structure shown in the accompanying drawings, in which—

Fig. I is a plan view of the device, open with a piece of fabric in place, ready for closure of the clamps as hereinafter described;

Fig. II is a view of the same structure as in Fig. I with the clamp closed and ready for sewing, a modified presser foot of the sewing machine being indicated;

Fig. III is a section of Fig. II on the line III—III of Fig. II; and

Fig. IV is a section of Fig. II at IV—IV of Fig. II.

In the drawings, 1 is a frame, offset at 1a for convenience in handling.

The frame 1 supports one relatively fixed jaw 2 and a movable jaw 3, the latter being pivotally attached to a slidable plate 4 by the pivot 5 to equalize its engagement with the jaw 2 or with cloth held between the jaws, represented by 6.

As shown, the reverse or "wrong side" of the piece of cloth is shown and the purpose of the setup in Fig. II is to sew an inlay 7 of identical material into the cloth 6 in such manner that the juncture or seam will be normally invisible and indeed difficult to find when one knows where to look, from the other or "right" side of the cloth.

As in the invention of the patent referred to, I fold the cloth around one of the jaws, preferably the fixed jaw 2 in such manner that a bight of the cloth containing the edges to be sewn together is about midway on the face of the jaw 2, with one part of the cloth folded back substan-

tially at right angles on top of the jaw and the other underneath the same jaw, all as shown in Fig. IV. The jaw 3 is then brought firmly into engagement with the cloth 6 as backed by the jaw 2, and locked in position.

The jaw 3 as mentioned is attached to and movable with the slidable plate 4 which is provided with parallel slots 8 and 9 within which are easily fitting pins 10 and 11, the pins being made rigid with the frame structure underneath the slots as shown in Fig. II.

A toggle lever 12 is attached to the slidable plate 4 by the pivot pin 13 and to a bell-crank lever 15 by the pivot pin 16. The bell-crank lever 15 is pivoted at 18 to an eccentric disc 19, adjustable at 20 to accommodate cloth of different thicknesses between the jaws 2 and 3.

It is thought that many other devices for holding the jaws together in locked position are usable and it is admitted that that shown is substantially old, hence needs no further description.

The essential difference between the device herein disclosed and the one patented is in parts now to be described, what has gone before being regarded as introductory.

With the device of the patent, I used two hard faced jaws with parallel needle grooves across their faces, requiring that sewing machine feed or stitch length be the same as groove spacing in all cases. This was quite easily accomplished but did not permit changing the length of the stitch to an extent deemed desirable since either the stitch had to be the same as the groove spacing, twice that or three times, no intermediate stitch length being practicable.

I now use one hard faced jaw, in this case the jaw 3, and roughen the face to sharp ridges by lengthwise milling as shown at 3a, though other forms of roughening are not excluded.

The other jaw, in this case 2, is provided with a face of resilient rubber, of about the resiliency of high grade tire tread stock, indicated by the numeral 2a, which may be attached in any suitable manner though I prefer to make the parts tongue and groove with the tongue on the rubber as shown in Fig. IV and fasten the rubber to the grooved metal backing part of the jaw by shellac or other suitable cement.

As with the device of the patent, the place where the needle 25 starts to penetrate the cloth 6 is critical, necessarily being in the line represented by the bight of vertical cloth between the jaws as shown at 6b in Fig. IV.

When the clamps are set on the cloth 6 and the line between the jaws is a right line with re-

spect to the forward feed of the sewing machine, the needle point always penetrates the cloth itself, entering on one side of the point of joinder and coming out again about the same distance 5 on the other side of what will be the "seam" on the same side of the cloth, the wrong side, as it entered. The resilient rubber yields enough to permit the needle to pass through without breaking the sewing thread and it appears that 10 there is a much better draw, that is the edges of the respective pieces of cloth are drawn together better than with the grooved device of the patent.

Since accurate guiding is even more critical 15 with this device than before, I provide a milled groove 21 in the hard faced jaw 3 that is parallel with the face of the jaw. I further provide a guide 28 that bears in the guide groove 21 and is attached to the modified presser foot 30.

20 It will be expedient to temporarily join the two pieces of cloth to be sewn together by basting, by tailor's adhesive tape or other preferred means. The "seam" may be made with tape reinforcement if desired for sleazy or loosely woven 25 materials though with firm stock its strength compares favorably with a single lapped seam of the old type. It may be used equally well for a long seam as for an inlay as shown.

The word rubber as used herein is intended to 30 embrace all materials having the well known resilient characteristics of rubber compounds and is not necessarily limited to those materials composed in part of material from the rubber tree.

Having disclosed my invention so that its principle 35 has become known and shown a preferred way of applying that principle, what I claim as new and desire to secure by Letters Patent, is—

1. In a device for sewing a bight of cloth containing two edges to be sewn together by blind 40 seaming, a pair of fabric holding means for holding abutting edges of a fabric in a bight for presentation to a sewing needle, one of said pair of holding means being of hard material roughened to grip the fabric and the other of said 45 pair of holding means being of resilient rubber, and means for guiding the pair of holding means to present the bight of cloth to the needle where it is held between the respective holding means.

2. A blind seam attachment for a sewing machine 50 comprising a frame, a pair of clamping

jaws on the frame that are adapted to present abutting edges of cloth to a sewing needle for entrance and egress on the same side of the cloth and means for guiding the jaw faces, in lines parallel with the line of progress of the 5 needle, characterized by the face of one jaw being of roughened hard material to engage the held cloth and the face of the other jaw being of resilient rubber.

3. A blind seam attachment for a sewing machine 10 comprising a frame, a pair of clamping jaws on the frame that are adapted to present abutting edges of cloth to a sewing needle for entrance and egress on the same side of the cloth and means for guiding the jaw faces in 15 lines parallel with the line of progress of the needle, characterized by the face of one jaw being of hard material to engage the held cloth and the face of the other jaw being of resilient rubber.

20 4. A sewing clamp for blind seaming, comprising a pair of opposed cloth holding means that are adapted to hold a bight of cloth therebetween for penetration by a sewing needle into and out of the cloth on the same side thereof, 25 said holding means having a hard, cloth holding face on one element of said pair and a resilient rubber, cloth holding means on the face of the other element of the pair, the hard face and the rubber face being arranged to engage opposite sides of the cloth at the point where the needle is to penetrate.

5. In a blind stitching device, a pair of cloth holding means that are adapted to firmly hold a bight 35 of cloth therebetween to present the bight for penetration of a sewing needle, in and out of the cloth on the same side thereof, means for holding the cloth firmly in proper relationship to a sewing needle and holding faces on said 40 holding means, characterized by at least one of said faces being of soft resilient rubber.

6. In a blind seaming device, a pair of clamping jaws, means for locking abutting edges of cloth between the jaws and means for guiding the jaws to present the cloth clamped between 45 the jaws to a sewing needle, the said jaws being characterized by a rigid cloth engaging face on one jaw and a soft resilient cloth engaging face on the other jaw.

JOHN JORDAN. 50
